UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

METHOD OF AND APPARATUS FOR PRODUCING AMMONIUM SULFATE.

1,322,757.

Specification of Letters Patent.

Patented Nov. 25, 1919.

Application filed February 15, 1916. Serial No. 78,444.

To all whom it may concern:

Be it known that I, HENRY A. CARPENTER, a citizen of the United States, and resident of Sewickley, in the county of Allegheny and State of Pennsylvania, have invented certain new and useful Improvements in Methods of and Apparatus for Producing Ammonium Sulfate, of which the following is a specification.

10 This invention relates to the production of sulfate of ammonia by subjecting coal gas to an acid saturation bath, the desired reaction resulting from contact of the ammonia laden gas with the sulfuric acid content of the 15 bath.

One object is to provide a controlled or predetermined uniform temperature condition within the saturator, and particularly at the gas outlet thereof, whereby the reaction 20 is caused to proceed under conditions most favorable for the production of high-grade sulfate, and whereby the temperature of the inlet gas may be so regulated as to insure vaporization of water from the bath in desired amount.

A further object is to utilize conditions inherent in the saturation bath for automatically controlling replenishment of the water and acid contents thereof, avoiding either 30 over or under supply and maintaining a saturation bath of uniform volume and acidity. The level of the bath is preferably utilized through the medium of a float for regulating the water additions, and the acid replenishment is determined by the specific 35 gravity of the bath by means of a hydrometer.

Another object is to produce an acid-free sulfate, and this I accomplish by thoroughly 40 washing the salt, waste being prevented by discharging the acid-carrying water into the saturator, and as the water which replenishes the bath may be used for this purpose, the desired conditions incident to the bath and 45 its maintenance are in no way disturbed. The washing is made very effective by causing the water to flow counter to and in contact with the sulfate as the latter is withdrawn from the saturator, whereby the sulfate is discharged free of acid.

Another object is to insure thorough and complete dissemination of the acid content throughout the saturation bath, the latter being usually about a 5% solution. The ad-

dition of a small amount of acid of great 55 concentration to the relatively large volume of the bath renders thorough mixing difficult if not impossible if attempted in that zone or portion of the bath entered by the gas. To circumvent this unfavorable condition I 60 maintain the bath in two bodies, with means for maintaining constant circulation between them. The reaction takes place in one of the bodies and the acid replenishment is accomplished in the other body, and by this 65 means a thorough and uniform mixture is had, particularly in that portion of the bath where the reaction takes place.

In Figures 1 and 2 of the accompanying drawings apparatus for practising the invention is illustrated, the showing in both views being largely diagrammatic, Fig. 1 illustrating the same primarily in side elevation with the various electric connections omitted, while in Fig. 2 the electrical circuits and 70 connections are shown, together with a vertical section of the auxiliary saturator bath chamber. Fig. 3 is a detail of the mechanisms actuated by the float and hydrometer for effecting the opening and closing of the 75 circuits controlled thereby. Fig. 4 is a view in vertical section of the main saturator chamber together with a form of conveyer for removing the sulfate therefrom, and Fig. 5 is a sectional plan of a portion of the chamber, taken on line 5—5 of Fig. 4. Fig. 6 is a view in vertical section of part of the structure mounted on the saturation chamber for supporting and operating the conveyer, the parts being illustrated at right angles to that 80 shown in Fig. 4. Fig. 7 illustrates one of the conveyer buckets in detail.

Referring to the drawings, 2 designates the saturator, and 3 the pipe for admitting coal gas thereto, the gas passing into the 95 upper compartment 4 of the saturator at the exterior of the dome 5. Space 4 is in free communication with the jacket-like space 6, the latter being formed by the downward continuation 7 of dome 5 and the outer wall 100 8 of chamber 2. Space 6 is in open communication beneath the level of the bath with the interior of the saturation chamber. From the chamber-encircling space 6 the gas is conducted into the hollow radially arranged distributing baffles 9, located beneath the level of the bath and each provided with a multiplicity of ports 10 for insuring effec-

tive distribution throughout all portions of the gas-entering zone of the bath. The pressure of gas is sufficient to depress the liquid level in space 6, so that the gas may freely 5 enter distributors 9, as shown in Fig. 4. Upon emerging from the bath the gas ascends into dome 5 from which it passes through discharge pipe 11.

It is desirable to regulate the temperature of the gas within the saturation chamber. One object of such regulation is to maintain the gas at an efficient absorbing temperature, whereby the water content of the bath will be depleted in such amount 10 that the water required to replenish the same will be sufficient to thoroughly wash the sulfate as it is withdrawn from the saturator, producing an acid-free salt. Another object of such regulation is to maintain the 15 temperature as low as is consistent with an efficient reaction, a better grade of sulfate being thus produced than when the temperature is excessive. A function of the saturator is availed of for accomplishing this 20 automatic regulation, and in the preferred practice the temperature of the gas discharging from the saturator is thus utilized.

In the embodiment of the temperature regulation here shown, 15 designates a gas 30 heater of usual construction through which a circulation of heated waste gases may be maintained by blower 16. The gas to be heated enters from a main 17 and discharges through pipe 18 into the saturator inlet 3. Extending around the heater from main 17 35 to inlet 3 is bypass 19, and controlling the flow to the heater and to the bypass is a damper 20 which is adapted to be actuated by an electric motor 21, which is by preference connected to a three-phase circuit 22 by a reversing switch 23 of familiar construction, and this switch is adapted to be actuated by a thermostat 24 of suitable type having its terminal 25 entered in the saturator gas outlet 11. By this means both 40 heated and relatively cool gas is passed to the saturator, the proportion of each being determined by damper 20 which, in turn, is controlled automatically by the temperature 45 at the saturator outlet, the reversing switch operating to actuate the motor in direction to admit more or less heated or cooled gas, or to remain inactive when the switch is in neutral position, all as determined by the movement emanating from 50 thermostat 24.

The invention embodies automatic regulation for controlling the replenishment of the water and acid contents of the saturation bath, but before describing these features reference will be made to the disposition of the bath in two separate bodies between which constant circulation of the liquid is maintained.

Upon referring to the drawings, it will

be seen that in addition to saturator 2 a supplemental chamber 30 is provided which is connected to chamber 2 by pipes 31 and 32. Pipe 31 leads from pipe 33 encircling chamber 2 and in communication with the latter at several points as indicated at 34. Connections 34 communicate with the upper or gas entering zone of the bath at 35, and as pipe 32 discharges into this zone, circulation is had between chamber 30 and that portion of the bath that is required to be of maximum acidity, *i. e.*, the portion with which the gas is in contact after discharging from baffles 9. Also, with the circulation outlet leading from the upper portion 30 of the saturation bath there is practically no withdrawal of sulfate into chamber 30. Circulation is maintained by means of a pump 36 driven by motor 37 and to which pipe 32 is connected, and by this means the 35 contents of chambers 2 and 30 are constantly mixing and interchanging.

The advantage of the foregoing arrangement results from the fact that the relatively small amount of acid of high concentration 40 is supplied to chamber 30 and is thoroughly mixed with the saturation bath in said chamber and before reaching chamber 2. Whereas, if the acid were introduced directly into chamber 2 there would be no 45 opportunity for obtaining a thorough mixing and to that extent the operation of the saturator would lack uniformity and its efficiency would be correspondingly lessened.

Functions of the saturation bath are 50 utilized for automatically controlling the inflow of water and acid, whereby the volume and acidity of the bath are maintained substantially constant. The water supply may be obtained from a main 40 which is adapted to discharge into the conveyer tube 41 (presently to be described) extending downwardly into saturator 2 and open to the lower portion of the latter. A valve 42 in pipe 40 is actuated by electric motor 43 which is connected in the three-phase circuit 22 by the reversing switch 44, similar in construction and operation to switch 23, and this switch 44 is operatively connected to the float 45 which by preference is arranged in the supplemental bath chamber 30. Motion is transmitted from the float to switch 44 by means of a lever 46 fulcrumed between its ends at 47 to the wall of chamber 30 and with its opposite ends pivotally connected, respectively, to the float and switch. By this means the flow of water through main 40 may be accurately controlled, motor 43 being controlled by the switch to either decrease or increase the flow or to maintain a predetermined constant flow, determined by the liquid level of chamber 30.

The supply of acid may be drawn from a suitable elevated container 50, a valve 51

controlling the flow therefrom into chamber 30. A reversible electric motor 52 for actuating this valve is connected in circuit 22, the direction of the motor being controlled 5 by a solenoid reversing switch conventionally shown at 53. This switch is under the control of hydrometer 54 located in chamber 30, the hydrometer stem 55 being movable through a vertical guide 56 carried by the 10 float and at its upper end pivotally connected to one end of lever 57. This lever is mounted between its ends on fulcrum 47, being thus fulcrumed coincidentally with lever 46. An interruption 58 in the branch of 15 the circuit extending to one side of switch 53 is movably supported at 59 by lever 46, and said interruption is adapted to be closed by the bridging contact 60 carried by one leg of lever 57 when the hydrometer has 20 risen sufficiently to effect such operation. A like interruption 61 in the branch of the circuit extending to the other portion of switch 53 is movably carried by the opposite leg of lever 46, and is adapted to be closed by the 25 bridging contact 62 movably carried by the portion of lever 57 that is distant from contact 60. As variations in the liquid level have substantially the same position-changing effect on the float and hydrometer, levers 46 and 57 have substantially the same 30 movement on their common fulcrum 47 in response to such variations. This results in maintaining the circuit interruptions 58 and 61 in substantially the same relation to contacts 60 and 62 irrespective of liquid level changes, and hence said parts are in proper 35 relation for controlling the direction of motor 52 by movement of the hydrometer relatively to the float, determined by the specific gravity of the bath.

The quality of ammonium sulfate is frequently seriously impaired by the presence of sulfuric acid which is of a viscous nature and adheres to the salt in such manner 45 that its removal presents a difficult problem. Also the acid removed from the bath with the sulfate is an element of waste. The present invention provides for effectively 50 washing the sulfate during its withdrawal from the saturator so that it is discharged from the apparatus in a non-acid state. The means here shown for accomplishing this purpose consists of an endless conveyer chain 55 within tube 41 and carrying perforated or open mesh buckets 66. This conveyer is mounted in tube 41 on the upper and lower sprocket wheels 67 and 68, respectively, journaled in the vertical parallel arms 69 of a supporting frame. The upper end of this 60 frame comprises a spindle 70 that is rotatable in bearings 71 of frame 72, the latter mounted on saturator 2, a motor 73 being geared to the spindle at 74 whereby the endless conveyer and its support are rotated 65 about a vertical axis without interfering

with the movement of the conveyer around the sprocket wheels.

For driving the conveyer chain, shaft 75 carrying the upper sprocket 67 has secured thereto pinions 76 which mesh with the circular downwardly facing rack 77 within frame 72, so that the movement of the conveyer support about its vertical axis operates to drive the upper sprocket, thereby keeping the conveyer in motion. Buckets 75 70 66 are thus caused to fill with sulfate at the lower end of tube 41 and discharge at the upper end of said tube.

The movement of the conveyer about a vertical axis combined with the vertical 80 travel of the buckets results in so agitating sulfate at the lower end of tube 41 as to maintain an ample supply within reach of the buckets at all times. Plow-like arms 79 projecting laterally from the lower extremity of frame 69, Figs. 4 and 5, sweep through the sulfate as the frame is rotated, thus still further agitating the same. At the upper end of the conveyer the inflowing fresh water is discharged from pipe 40 90 through the ring or manifold 48 so that the sulfate is thoroughly washed while being elevated through tube 41 and is freed of the acid adhering thereto, the water draining therefrom through the ascending perforated 95 buckets.

It is characteristic of the cleansing operation that the sulfate and water move or flow in opposite directions through a common path of substantial length with the 100 scrubbing action proceeding from end to end thereof. The sulfate encounters progressively clearer or fresher water as it moves toward the discharge end of the conveyer, whereby a most effective washing and rinsing 105 action is had. While this contra-current washing is preferably practised with the water which replenishes the bath, and while in such practice the temperature regulation of the saturator is such as to require 110 an amount of inflowing water sufficient to thoroughly cleanse the sulfate, the invention is not restricted thereto.

I claim:

1. In the production of sulfate of ammonia by treating coal gas in an acid saturation bath, the method herein described of freeing the sulfate of acid, consisting in subjecting the sulfate to a cleansing liquid, with the latter and the sulfate moving in opposite 120 directions during the cleansing process.

2. In the production of sulfate of ammonia by treating coal gas in an acid saturation bath, the method herein described of freeing the sulfate of acid, consisting in 125 withdrawing the sulfate from the bath and during such withdrawal subjecting it to a stream of water flowing oppositely thereto.

3. In the production of sulfate of ammonia, the method herein described, con- 130

sisting in introducing coal gas into an acid saturation bath in condition to cause it to absorb water from the bath, replenishing the water content of the bath, and simultaneously withdrawing the ammonium sulfate in opposite direction to the entering water and in contact therewith.

4. In the production of sulfate of ammonia, the method herein described, consisting in introducing coal gas into an acid saturation bath in condition to cause it to absorb water from the bath, elevating and thereby withdrawing the ammonium sulfate from the bath, and replenishing the water content of the bath by introducing water thereinto in contra-current to the discharging sulfate and in contact therewith.

5. In apparatus for producing sulfate of ammonia, a saturator containing an acid bath adapted to receive coal gas and form ammonium sulfate, means for withdrawing the sulfate, and means for washing the sulfate as it is being withdrawn.

6. In apparatus for producing sulfate of ammonia, a saturator containing an acid bath adapted to receive coal gas and form ammonium sulfate, and a source of water for replenishing the bath with the water moving oppositely to and in contact with the sulfate as the latter is withdrawn.

7. In apparatus for producing sulfate of ammonia, a saturator containing an acid bath adapted to receive coal gas and form ammonium sulfate, a conveyer for removing the sulfate from the bath, and means for bodily shifting the conveyer relatively to the accumulation of sulfate within the saturator for causing the conveyer to act on different portions of such accumulation.

40 8. In apparatus for producing sulfate of ammonia, a saturator containing an acid bath adapted to receive coal gas and form ammonium sulfate, an endless vertically movable conveyer extending upwardly from the lower portion of the saturator, a conveyer support, and means for moving the support about a vertical axis.

9. In apparatus for producing sulfate of ammonia, a saturator containing an acid bath adapted to receive coal gas and form ammonium sulfate, a support extending up-

ward from the lower portion of the saturator and rotatable about a vertical axis, upper and lower sprocket wheels carried by the support, and an endless bucket elevator moving around the sprocket wheels.

10. In apparatus for producing sulfate of ammonia, a saturator containing an acid bath adapted to receive coal gas and form ammonium sulfate, an endless conveyer extending upwardly from the lower portion of the saturator and movable bodily independently of its sulfate elevating movement, and means for driving the conveyer and for simultaneously moving it bodily.

11. In apparatus for producing sulfate of ammonia, a saturator containing an acid bath adapted to receive coal gas and form ammonium sulfate, a tube extending upwardly through the saturator and open to the lower portion of the latter, the upper portion of the tube open at the exterior of the saturator for discharging sulfate, and a conveyer operative within the tube for withdrawing sulfate from the saturator.

12. In apparatus for producing sulfate of ammonia, a saturator containing an acid bath adapted to receive coal gas and form ammonium sulfate, a tube extending upwardly through the saturator and open to the lower portion of the latter, the upper portion of the tube open at the exterior of the saturator for discharging sulfate, a conveyer support rotatable in the tube about a vertical axis, and a conveyer mounted on the support.

13. In apparatus for producing sulfate of ammonia, a saturator containing an acid bath adapted to receive coal gas and form sulfate of ammonium, a sulfate removing conveyer for withdrawing the sulfate from the bath, and a source of water for replenishing the bath with such water flowing through the conveyer in contra-current to the discharging sulfate.

In testimony whereof, I affix my signature in presence of two witnesses.

HENRY A. CARPENTER.
